CUTTING INSTRUMENT PARTICULARLY
USEFUL IN CONNECTION WITH COR-
NEAL GRAFTING

Gaëtan Jean-Edward Jayle, New York, N. Y.

Application March 8, 1948, Serial No. 13,624

10 Claims. (Cl. 128—305)

1

This invention relates to a cutting instrument particularly useful in connection with corneal grafting, and to apparatus for the treatment of ocular and other conditions generally.

The principal object of this invention is the provision of a cutting instrument of the character described which is adapted to cut the cornea obliquely in such manner that the anterior end of the cornea aperture is smaller than the posterior end. Conventional cutting instruments used in corneal grafting are provided with cylindrical cutting heads and they are, therefore, adapted to remove a cylindrically shaped portion of the cornea preparatory to the grafting operation. The instrument herein claimed, however, is adapted to cut obliquely into the tissue to remove a section thereof which has the shape of a truncated cone. The advantages inherent in such oblique cutting are very substantial. Since the corneal graft or transplant will be of the same shape as the aperture which is cut in the cornea, and since the anterior ends both of the hole and of the graft are smaller than their respective posterior ends, once the graft is properly inserted into the hole, it will resist outward displacement therefrom. This is especially important when the anterior chamber refills with fluid and the fluid pressure against the graft tends to push it out of the corneal hole. Another substantial advantage in cutting the cornea obliquely is the provision of a larger contact area or surface between the graft and the wall of the corneal hole. The greater this contact area, the more surely will the transplant become nourished by and united with the corneal tissue remaining in the eye, thereby insuring positive adhesion and growth.

Another object of this invention is the provision of a pressure chamber usable in connection with the cutting instrument herein claimed to prevent collapse of the eye during the course of and by reason of the surgical operation and to enable the cutting instrument to cut completely through the cornea without injury to the iris or lens or any other tissue which lies immediately adjacent the cornea or the anterior chamber. In corneal grafting and other similar surgical operations, a trepan or trephine is used to cut partly through the cornea and another cutting instrument such as a pair of scissors must be used to complete the cutting operation. These two steps are generally found necessary to avoid injury to the tissue behind the cornea when the eye collapses.

In the present invention, however, a pressure

2

chamber is provided to prevent escape of the fluid from the corneal chamber during the process of cutting and removing the diseased portion of the cornea. It is, therefore, possible, using this pressure chamber, to cut completely through the cornea without injury to other tissue of the eye since the cornea remains spaced from the iris and the lens at all times during the cutting operation.

10 The pressure chamber may also be used for post-operative work as for treating of the eye or eyes to promote healing, etc. In such case, the implement is removed from the pressure chamber and the opening is closed by a screw plug, not shown. Pressure may then be applied to maintain the graft in place until knitting of the tissue has occurred. Also, if desired, liquid or gas may be introduced for stimulating healing and for antibiotic and antiseptic purposes.

15 It will be understood that although the invention is herein described in connection with corneal grafting operations, it is also suitable for use in connection with surgical operations of other types, especially relating to the eye, but not necessarily so. It will further be understood that although the invention is herein described relative to surgical operations and to living tissue, it may be adapted to other cutting operations and in connection with matter and material other than living tissue.

20 It will also be understood that the mask or pressure chamber may be used for other medical and physiological purposes where it is desired to use pressure with gas or liquid heating or nutritive material. Such mask is useful where protracted treatment of the eyes is necessary, in which case the mask or pressure chamber may be placed over the patient's eye or eyes and gas or liquids may be circulated around the eye ball for extended periods with ease and with little discomfort to the patient.

25 Preferred forms of this invention as shown in the accompanying drawing, in which:

Fig. 1 is a side elevation thereof.

30 Fig. 2 is a fragmentary back view of said instrument, showing the means by which its effective or operative height may be adjusted.

35 Fig. 3 is an enlarged fragmentary view of the cutting head of the instrument, showing it in vertical section.

40 Fig. 4 is a horizontal section therethrough, on the line 4—4 of Fig. 3.

45 Fig. 5 is a fragmentary detailed view in vertical section of the blade or knife holder and of

the means for extending the blade longitudinally during the course of the cutting operation.

Fig. 6 is a side view of a modified form of blade or knife usable in connection with the cutting instrument shown in the first five figures of the drawing.

Fig. 7 is an enlarged fragmentary view of the cutting head showing it mounted in a pressure chamber which is placed upon the eye-ball, said pressure chamber being shown in vertical section.

Fig. 8 is another fragmentary view of the cutting head of the instrument, showing it mounted in another type of pressure chamber which is placed around the eye rather than directly upon it, said pressure chamber being shown in vertical section.

Fig. 9 is a front view of a pair of pressure chambers of the type shown in Fig. 8, said pressure chambers being connected to each other for simultaneous mounting on the head of a patient who requires surgical treatment of both eyes at the same time.

Referring now to the first six figures of the drawing, it will be seen that the instrument herein claimed is provided with a base or stand 10, having a post or column 11 mounted thereon, vertically thereof. At the top end of column 11 is a screw 12 accommodating a slidably mounted housing 13 and an adjusting nut 14. Housing 13 rests on nut 14 and its position on screw 12, and hence its height from the floor, is determined by the position of the nut on said screw. The nut may be turned either clockwise or counter-clockwise to lower or raise the housing. The top end of housing 13 is split or bifurcated and a clamping screw 15 is provided to clamp said bifurcated end of the housing to screw 12 after the nut has been actuated to bring the housing to its desired location on screw 12.

Affixed to vertically extending housing 13 is a horizontally extending housing 20, and telescopically mounted in said horizontal housing 20 is a horizontally extending tubular member 21 on which the cutting head 22 is mounted. Tubular member 21 may be moved both axially and angularly in horizontal housing 20, and it will be noted that said housing is also bifurcated at one end thereof and that it is provided with a clamping screw 23 to clamp said bifurcated end tightly upon tubular member 21 to fix said tubular member in place in said horizontal housing 20. It will be understood that the construction last above described is designed to adjustably position the cutting head 22 relative to the patient in order to bring it into the best and most convenient operative position. Other clamping and adjusting means may be used for the purposes indicated than those herein above mentioned and described.

An electric motor 25 is mounted on base 10 and it is this motor which provides the motive power for the cutting instrument herein described. It is connected by means of a flexible shaft 26 and a pair of horizontally extending shafts 27 and 28 to a vertically extending hollow drive shaft 29 in the cutting head. It is to this drive shaft that the blade holder 30 and blade 31 are attached, and by means of which they are caused to rotate. More specifically, it will be noted that the upper end of flexible shaft 26 is provided with a gear wheel 35 which engages another gear wheel 36 which is mounted at one end of shaft 27. At the opposite end of said shaft is a flexible joint 37 by which said shaft is connected to shaft 28. A gear wheel 38 is affixed

to shaft 28 and said gear wheel engages another gear wheel 39 which is affixed to vertically extending drive shaft 29 by means of nut 40. Bearings 42 and 43 position shaft 29 in housing 22. It will be seen that bearing 42 is carried between seat 45 in housing 22 and a nut 46 on shaft 29, and it will also be seen that bearing 43 is mounted between a seat 47 in housing 22 and a shoulder 48 on said shaft 29 where said shaft is connected to the blade holder 30. The blade holder and hence the blade may be caused to engage in rotary movement by means of motor 25 irrespective of the position which the cutting head occupies with respect to said motor.

The cutting member 31 comprises a shank 50 and a blade or cutter proper 51. A transversely extending pin 52 is fastened to shank 50 and it will be seen that said pin serves as a stop member against which a compression spring 53 extends. A cylindrical bearing 55 is provided for cutting member 31, and it will be seen that said bearing member is mounted for angular movement in the cutter holder 30, on a horizontal axis, that is, an axis which extends perpendicularly with respect to the axis of drive shaft 29. Bearing 55 has a diametrically extending hole formed therein which accommodates a shank 50 of the cutting member. It is thus possible for the cutting member to move longitudinally of itself through the hole in said bearing and also to move pivotally about the axis of said bearing, integrally with said bearing.

Cutting member 31 occupies a diagonally extending hole 60 formed in holder 30. The angle between the longitudinal axis of said hole and the longitudinal axis of drive shaft 29 should be predetermined, depending upon the angle at which it is desired to cut the diseased cornea from the eye. Hole 60 is sufficiently large to enable cutting member 31 to pivot with bearing 55 about the axis of said bearing. It has been mentioned that pin 52 extends through the shank of cutter 31 and that a spring 53 bears against said pin. The opposite end of the spring bears against the wall of holder 30 which is at the lower end of hole 60, and it will be apparent therefore that said spring tends to urge the cutter to move upwardly, longitudinally thereof.

Along one side of shank 50, at its upper end, are teeth 61 which, together with shank 50, comprise a rack gear. Engaging said rack gear is a pinion 62 mounted in holder 30, and it will be seen in Fig. 5 that said pinion engages a second rack gear 63. Rack gear 63 is a rod having teeth formed at its lower end. The rod extends through hollow drive shaft 29 and at its upper end it is mounted within a bearing 66. The bearing is mounted in a piston-like member 67 mounted for vertical movement in housing 22. A compression spring 68 bears against the top of said piston-like member and a cap 69 is provided at the top of housing 22 to serve as an upper bearing for spring 68, thereby enabling said spring to urge the piston-like member to move downwardly in housing 22. Rod 63 is adapted to rotate in bearing 66 but relative angular movement between said rod and hollow drive shaft 29 is prevented by pin 70 extending through rod 63 and riding in vertically extending slots 71 formed at the upper end of shaft 29. Although this pin and slot arrangement prevents angular movement of rod 63 relative to drive shaft 29, it permits axial movement of said rod relative to said shaft. A set screw 75 is provided in housing 22 to engage piston-like member 67 when it is de-

sired to prevent relative movement between said member and the housing. A cam-shaped lever 76 pivoted on 77 and having a handle 78 is provided in housing 22 to engage the lower end of piston-like member 67 to move said member upwardly against the action of spring 68 or to release said member for downward movement in response to the action of said spring. It has been indicated that rod 63 is adapted to rotate within bearing 66 of piston-like member 67, but it will be understood that axial movement of said rod relative to said piston-like member will be prevented by reason of the clamping action which exists between shoulder 79 and nut 80 at the upper end of rod 63 on the one hand, and the inner rows of bearing 66 on the other hand. Hence, vertical movement of the piston-like member 67 will be productive of corresponding vertical movement of rod 63.

It has been stated that rod 63 is provided with gear teeth at its lower end and that it therefore constitutes the rack gear which engages pinion 62. Since the pinion also engages rack gear teeth of cutter 31, a downward movement of rod 63 will cause an upward movement of the cutter and an upward movement of the rod will cause a downward movement of the cutter. A leaf spring 81 is provided to hold the rack gear teeth of the cutter in engagement with the teeth of pinion 62.

When it is desired therefore to move the cutter downwardly along its longitudinal axis, handle 78 should be depressed, thereby causing cam lever 76 to force the piston-like member 67 to move upwardly against the action of spring 68 and to carry rod 63 upwardly simultaneously therewith. The upward movement of said rod 63 will, therefore, cause the cutter to move downwardly. When it is desired to raise the cutter, handle 78 should be released to the desired extent, thereby permitting spring 68 to lower piston-like member 67 and rod 63. The downward movement of the rod will of course produce an upward movement of the cutting member.

It will be understood that no conflict arises between the vertical movement of rod 63 and the axial movement of cutter 31 on the one hand, and the rotary movement of drive shaft 29 and cutter holder 30 on the other hand. Rod 63 rotates integrally with the drive shaft and with the cutter holder 30, and hence it remains in uninterrupted engagement with pinion 62, and said pinion remains in uninterrupted engagement with the teeth of the cutting member 31. Angular movement of the cutter about the axis of the drive shaft may, therefore, be had simultaneously with axial movement either upwardly or downwardly of said cutter. It should be understood at this point that spring 53 is supplied to provide a smoother axial movement of the cutter in response to the actuation of cam lever 76 and to prevent back lash in the rack and pinion connection above described.

The cutting angle of the cutter is substantially fixed in the form of invention shown in Fig. 3. If it be desired to vary the cutting angle within the limitations imposed by the construction of the cutting head as shown in Fig. 3 of the drawing, then a plurality of cutters such as cutter 90 should be provided in place of or in addition to cutter 31. Cutters 90 differ from cutter 31 solely in the width of the shank where rack gear teeth 91 are provided. Cutters 90 are provided with varying shank thicknesses to increase or lessen the distance between the longitudinal axis of the cutter 75 and the central axis of the pinion which the rack gear teeth of the cutter engage. Since cutter 90 is pivotally mounted in its holder, these varying distances between the longitudinal axis of the cutter and the central axis of the pinion will make for correspondingly different cutting angles which the cutter will present to the tissue, and also allow for varying the diameter of the hole which can be cut.

It will be noted in Figs. 3 and 5 that the cutting member 31 extends diagonally across the longitudinal axis of drive shaft 29. It is this arrangement that enables the cutter to cut a cone-shaped or truncated cone-shaped hole, the smaller diameter of the hole being at its outer end and its larger diameter being at its inner end. Should it be desired to produce a hole of cone or truncated cone shape whose larger diameter is at its outer end and whose smaller diameter is at its inner end, the cutter should be so positioned in its hole 60 that its cutting blade does not extend across the longitudinal axis of drive shaft 29. The cutter would still remain positioned an acute angle removed from longitudinal axis of drive shaft 29.

25 The pressure chamber above referred to is shown in Fig. 7 and in slightly modified form in Fig. 8. In Fig. 7, it will be seen that a transparent tubular member 100 is screwed to the lower end of housing 101 which corresponds to housing 22 above described. A suction ring 103 or a sealing ring of any suitable material is fastened to the lower end of tubular member 100, and it will be noted that said ring is adapted for engagement with the eyeball 104 to provide an air- and liquid-tight closure therewith. Contained in said tubular member 100 is a suitable liquid 105 which is non-injurious to the tissue of the eye. Suitable means are employed to provide a greater pressure in fluid 105 than normally exists in the fluid in the anterior chamber 104a of the eye. Hence, it is possible, using this device, to cut completely through the cornea 104b and yet to prevent escape of the fluid from the anterior chamber 104a. It is clear, therefore, that the use of this device 40 prevents collapse of the eye during the course of the operation and permits of cutting completely through the cornea without danger of injuring the tissue behind it.

It has been stated that tubular member 100 is 50 made of transparent material, the reason being that it must serve as a window in addition to serving as a pressure chamber to enable the surgeon to see what he is doing. To prevent or at least reduce refraction, a conical portion 106 is provided 55 in the wall of member 100. The radial lines of said conical wall portion 106 extend substantially at right angles across the line of vision from the eye of the surgeon to the eye of the patient, thereby enabling the surgeon to see the cutting operation very clearly and to enable him to control it as well as is humanly possible.

In Fig. 8 the cup-shaped member 110 corresponds to the tubular member 100 of Fig. 7. It is much larger, however, and its suction ring 111 is 65 enabled to make contact with the nose, cheek, and brow of the patient. Here too, a liquid-tight and air-tight closure is provided, and fluid under controlled pressure is brought into chamber 110 through tubular member 112. In Fig. 9 two such chambers 110 are shown joined by means of a tubular member 113. Straps 114 are used to fasten the two members 110 to the head of the patient.

It will be understood that the foregoing is descriptive solely of a preferred form or preferred

and the central axis of the pinion which the rack gear teeth of the cutter engage. Since cutter 90 is pivotally mounted in its holder, these varying distances between the longitudinal axis of the cutter and the central axis of the pinion will make for correspondingly different cutting angles which the cutter will present to the tissue, and also allow for varying the diameter of the hole which can be cut.

forms of this invention and that modifications and variations may be incorporated therein within the broad principles of the invention.

Having thus described my invention, what I claim as new and desire to secure by Letters Patent, is:

1. A cutting instrument of the character described, comprising a motor driven drive shaft and a cutting member connected to said drive shaft for rotation therewith, said cutting member being mounted at an acute angle relative to the longitudinal axis of said drive shaft and extending across said longitudinal axis.

2. A cutting device of the character described, comprising a rotatable drive shaft, means connected to said drive shaft causing said drive shaft to rotate, and a cutter mounted on said drive shaft and movable integrally therewith, said cutter being mounted at an acute angle relative to the longitudinal axis of the drive shaft and extending across said longitudinal axis.

3. A cutting device of the character described, comprising a motor-driven, rotatably mounted drive shaft, a cutter mounted on said drive shaft at its free end and positioned thereon at an acute angle relative to the longitudinal axis of said drive shaft and extending across said longitudinal axis, said cutter being rotatable with said drive shaft and being also movable longitudinally of itself and across the longitudinal axis of the drive shaft, and control means for controlling said longitudinal movement of the cutter.

4. A cutting device of the character described, comprising a rotatably mounted motor-driven drive shaft, a cutter holder mounted at the free end of said drive shaft and rotatable integrally therewith, a cutter mounted in said holder and extending across the longitudinal axis of said drive shaft, said cutter being movable longitudinally of itself, and control means geared to said cutter for causing longitudinal movement thereof at the same time that said cutter rotates with the drive shaft.

5. A cutting device of the character described, comprising a rotatably mounted motor-driven hollow drive shaft, a cutter holder mounted at the free end of said drive shaft, a cutter mounted in said holder at an acute angle relative to the longitudinal axis of the drive shaft and extending across said longitudinal axis, said cutter being movable longitudinally of itself, gear teeth provided on said cutter, a pinion provided in said holder in engagement with the cutter gear teeth, a rack gear extending through the hollow drive shaft, and control means for controlling said rack gear being fixed against angular movement relative to said drive shaft but being free to move longitudinally thereof, and control means for controlling the longitudinal movement of said rack gear to effect longitudinal movement of the cutter through the pinion connection therewith.

6. A cutting device of the character described, comprising a rotatably mounted motor-driven hollow drive shaft having a cutter holder at its free end, said cutter holder having a cutter mounted therein at an acute angle relative to the longitudinal axis of the drive shaft, said cutter being movable longitudinally of itself across said longitudinal axis of the drive shaft, rack and pinion means in the holder and connected to the cutter for causing longitudinal movement of said cutter, and a control member connected

10 to said rack and pinion means through the hollow drive shaft, said control member being movable longitudinally of said drive shaft to control the rack and pinion means and thereby to control the longitudinal movement of the cutter, said control member being integrally rotatable with the drive shaft, tension means urging the control member to move in one direction longitudinal thereof and lever means connected to said control member for causing said control member to move in the opposite longitudinal direction against the action of the tension means.

15 7. A cutting device of the character described, comprising a rotatably mounted motor-driven hollow shaft, a cutter holder mounted at the free end of said shaft, a cutter mounted in said holder for integral rotary movement therewith, said cutter being also adapted for movement longitudinally of itself relative to said holder, said cutter being positioned at an acute angle relative to the longitudinal axis of the drive shaft and extending across said longitudinal axis, rack gear teeth provided at the non-cutting end of the cutter, a pinion engaging said teeth mounted in said holder, and a rack gear engaging said pinion to control the longitudinal movement of said cutter, said rack gear extending through the hollow shaft and rotatable integrally therewith, said rack gear being also movable longitudinally of itself in said hollow drive shaft and being provided with tension means tending to urge it to move longitudinally of itself in one direction, and lever control means operatively connected to said rack gear for causing its movement in the opposite longitudinal direction against the action of the tension means.

20 8. A cutting device in accordance with claim 7, in which the angular distance separating the cutter from the longitudinal axis of the drive shaft is determined by the width of the cutter at its rack teeth end, said cutter being pivotally mounted in said holder on an axis which intersects its own longitudinal axis at right angles thereto.

25 9. A cutting device in accordance with claim 7, a fluid-containing member surrounding the cutter holder and the cutter, said member being open to the eye of the patient and being provided with a suction ring to provide a liquid-tight and air-tight closure therewith, and means maintaining the liquid in said member under pressure, said member being provided with a transparent wall through which the surgeon may witness and control the cutting operation.

30 10. In a cutting device of the character described, a cutting element, a fluid-containing member surrounding said cutting element and open to the eye of the patient, a suction ring provided on said liquid-containing member to provide a liquid-tight and air-tight closure between said member and the area surrounding the operative region of the patient's eye, and means maintaining the liquid in said member under pressure greater than the pressure of the fluid in the anterior chamber of the eye, said member being provided with a transparent wall through which the cutter and the patient's eye may be seen.
